VENTILATING APPARATUS

John D. Strobell, New Haven, Conn., assignor to
The Safety Car Heating & Lighting Company,
a corporation of New Jersey

Application December 7, 1937, Serial No. 178,452

10 Claims. (Cl. 98—13)

This invention relates to car ventilation, and more particularly to ventilating apparatus for a railroad car or the like.

One of the objects of this invention is to provide ventilating apparatus for a railroad car or the like which is simple and inexpensive in construction and sturdy and durable under conditions of extended use. Another object is to provide apparatus of the above nature which may easily be attached to a car without extensive alteration of the car. Another object is to provide apparatus of the above nature which operates efficiently and does not detract from the appearance of the car. Another object is to provide apparatus of the above nature which is effective regardless of the direction of travel of the car. Another object is to provide apparatus of the above nature which effectively introduces fresh air into the car while hindering or preventing the admission of moisture and other foreign particles. Other objects will be in part apparent and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawing, in which is shown one of the various possible embodiments of my invention,

Figure 1 is a diagrammatic perspective view of a railroad car having my ventilating apparatus installed therein;

Figure 2 is a side elevation of my ventilating apparatus, portions thereof being broken away; and,

Figure 3 is a sectional elevation taken along the line 3—3 of Figure 2.

Similar reference characters refer to similar parts throughout the various views of the drawing.

In order that various of the novel features of my invention may be more readily understood, it might here be noted that many railroad cars are equipped with air conditioning apparatus which needs a substantially continuous supply of fresh air. The usual type of air intake is not satisfactory because due to the speed of the car areas of low pressure are established, resulting in reduced air quantity and in some cases an exhausting action. Intakes often applied to so-called streamline cars detract from the appearance of the car and are often so arranged as to prevent access to the filtering medium from a

position outside of the car. It is accordingly another object of this invention to provide ventilating apparatus for a railroad car or the like which effectively overcomes these difficulties.

Referring now to Figure 1 of the drawing, a railroad car or the like is generally indicated at 10 and illustratively is of the so-called "streamline" type, having a roof 11 of round or flat oval cross section. Roof 11 includes a relatively flat portion 11a and a hip or curved portion 11b. In many instances cars of this type either have a relatively small vestibule such as vestibule 17 at one end thereof, or none, such as when the cars are secured together as articulated units. Where the car is provided with one or more vestibules, it is sometimes advisable to provide a fresh air inlet for ventilation purposes in the vestibule. It often happens, however, that this location of the air inlet is impractical because of the arrangement of air conditioning apparatus in the car, and of course where the car has no vestibule, other provisions for fresh air inlet must be made.

To this end, and with further reference to Figure 1, I have provided a ventilator generally indicated at 12, mounted in hip or curved portion 11b of car roof 11. Generally speaking, ventilator 12 includes a frame 13 bordering an opening 40, across which a plurality of louvers 16 extend, these louvers being formed and arranged to prevent or materially impede the passage of moisture, soot, or other particles into the car, as will be described in greater detail below. At the transverse edges 13a and 13b of frame 13, I mount a pair of deflectors 14 and 15, which, regardless of the direction of travel of car 10, deflect air into the inlet past louvers 16.

It should be noted at this point that when a car is traveling at high speed, the high relative velocity of air across an opening, such as opening 40, results in the formation of a low pressure area at the leading or forward edge of the opening. The effect of this low pressure is to exhaust air from the car, rather than cause a flow thereof into the car, and even where an intake fan is provided, the predetermined and desired amount of fresh air cannot be sucked in. However, by the provision of deflectors 14 and 15, the formation of the above-noted low pressure areas is effectively precluded as these deflectors or vanes 50 act as scoops regardless of the direction of travel of the car to force the fresh air into the car.

Referring now to Figure 2, transverse frame edges 13a and 13b have secured thereto respectively deflector supports 18 and 19, as by screws 55

20, two supports preferably being provided for each deflector. Supports 18 and 19 have outer edges 18a and 19a which are inclined with respect to the plane of frame 13, and which are oppositely inclined with respect to one another. Deflectors 14 and 15 are secured to support edges 18a and 19a in any suitable manner as, for example, by spot welding.

As noted above, ventilator 12 (Figure 1) is preferably mounted on the hip or curved portion 11b of roof 11. Accordingly, frame 13 (Figures 1 and 2) is curved to the contour of roof hip 11b. It follows that deflectors 14 and 15 are similarly curved, and because of the inclination of support edges 18a and 19a, deflector edges 14a and 15a are spaced farther from the car roof than deflector edges 16b and 15b. Thus deflectors 14 and 15 are also inclined with respect to the plane of roof hip 11b and are oppositely inclined with respect to one another, so that regardless of the direction of travel of the car, one of the deflectors leads and the other follows, so as to force air into the car. Preferably, deflectors 14 and 15 are spaced to the right and left, respectively, of frame edges 13a and 13b, as viewed in Figure 2, so as to position deflector edges 14a and 15a substantially directly over the transverse edges 40a and 40b of opening 40. Thus a substantial space is provided between the inner surfaces of deflectors 14 and 15 and opening 40, as it is in those portions of the frame opening lying directly below deflectors 14 and 15 where the above-noted low pressure areas would occur, were it not for the deflectors.

35 Still referring to Figure 2, frame 13 includes longitudinal frame edges 21 and 22, and as is more clearly shown in Figure 3, frame edges 13a, 13b and 22 are preferably L-shaped in cross section, edge 13a accordingly having a depending portion 23, and edge 22 having a depending portion 24. Frame edge 21 also has an obliquely extending portion 25. Thus frame edge portions 23, 24 and 25 effectively strengthen the frame as a unit, and furthermore serve purposes described below.

45 As noted above with respect to Figure 1, opening 40 has louvers 16 extending preferably longitudinally thereacross. With reference to Figure 3, louvers 16 are provided with a flange 16a at each end, and these flanges are secured in any suitable manner to the depending portions of frame edges 13a and 13b as, for example, portion 23 of frame edge 13a. Louvers 16 are preferably inclined with respect to the horizontal and at their top edges have a lip portion 16b. As louvers 50 16 are arranged in staggered relationship and have lips 16b, the passage of moisture or other foreign particles through frame 13 into the car is largely prevented.

60 It may now be seen that louvers 16 and deflectors 14 and 15 are all secured to frame 13, these three parts accordingly constituting an integral unit. With reference to Figure 3, the unit comprising the frame, louvers and deflectors is mounted in the inlet end of an air duct 26 or the like, which extends into car 10 and may be connected, if desired, to air conditioning apparatus. In many instances it is desirable to provide supplemental filtering apparatus (not shown) in air duct 26, and these filters should be 65 accessible for purposes of replacement or repair. To this end, ventilator unit 12 is preferably hingedly connected to the inlet end of duct 26, preferably by suitable hinges 27, the leaves of which are secured respectively to depending portion 24 of frame edge 22, and a bracket 28 se-

cured in any suitable manner to car roof 11. To detachably maintain ventilator unit 12 in its operative position, suitable securing screws 29 (Figures 2 and 3) are rotatably mounted in suitable journals 30 (Figure 3) secured to frame edge 21, the threaded ends 29a of screws 29 extending inwardly into duct 26 where they may be threaded through suitable bolts 31, or the like, riveted or otherwise secured to the bottom of ducts 26. Preferably a stop 32 is also bolted to duct 26 to limit the inwardly swinging movement of ventilator unit 12.

It may now be seen that motion of car 10 in either direction of travel results in a positive flow of air through ventilator 12, deflector 14 or 15 effectively preventing the formation of low pressure areas in the inlet end of duct 26 (Figure 3). Furthermore, access to the interior of the duct is readily had through the manipulation of securing screws 29 which, when unthreaded from 20 bolts 31, permit opening or clockwise swinging (Figure 3) of ventilator unit 12. Still further, as deflectors 14 and 15 are preferably as long as opening 40 is wide, the deflectors may be relatively small and accordingly do not extend any 25 substantial distance outwardly of the car, thus keeping well within the clearance limits of the car, and not detracting from the "streamlined" effect thereof.

Accordingly I have provided ventilating apparatus for a railroad car or the like by which the various objects noted hereinabove are attained in a thoroughly practical and efficient manner.

As many possible embodiments may be made of the above invention, and as many changes 35 might be made in the embodiment above set forth, it is to be understood that all matter hereinbefore set forth, or shown in the accompanying drawing, is to be interpreted as illustrative and not in a limiting sense.

I claim:

1. The combination with a railway car, of means to deliver air to the interior of the car comprising, means forming an air inlet with an opening through an outer wall of the car which wall extends substantially in the direction of car movement, and means to deflect air into said air inlet comprising a vane having two edges extending at right angles to the direction of car movement and spaced from said opening and extending therealong, said vane being positioned with one of said edges spaced a greater distance from said opening than the other of said edges so that it deflects air into said opening when the car is moving.

2. In railway car construction, an outer wall structure the outer surface of which extends in the direction of car movement, means forming an air inlet with an inlet opening through said wall structure, and means to deflect air into said air inlet comprising a vane mounted on the exterior of the car and spaced outwardly from said opening, said vane extending substantially parallel to the outer surface of said wall structure and at right angles to the direction of movement 65 of the car with a space between said vane and said wall structure through which air flows to said opening.

3. In combination with a railway car in which air is delivered to the interior of the car, an air 70 inlet means having an inlet opening flush with the surface of the car extending in the direction of car movement, means to deflect air into said inlet means through said opening comprising a vane extending parallel to the plane of said open- 75

ing and substantially at right angles to the direction of car movement, said vane being spaced from the outer surface of the car a sufficient distance to cut the air adjacent the car during car movement and when the car is moving in one direction said vane having a leading edge and a trailing edge with a leading surface to deflect air toward said opening—whereby movement of the car in said predetermined direction causes 10 said vane to cooperate with the adjacent surface of the car to create high pressure air conditions in the immediate vicinity of said opening.

4. The combination with a railway car, of means to deliver air to the interior of the car comprising, means forming an air inlet with an opening the mouth of which is in a plane extending in the direction of car movement, one edge of said opening being a leading edge when the car is moving in one direction, and means to 15 deflect air into said air inlet comprising a vane having two edges extending along and spaced from said leading edge of the opening, said vane being positioned with one of said edges spaced a greater distance from said opening than the 20 other of said edges so that it deflects air into said opening when the car is moving in one direction.

5. In railway car construction, an outer wall construction the plane of the outer surface of which extends in the direction of car movement, 30 means forming an air inlet with an opening through said wall structure, and means to deflect air into said air inlet comprising a flat vane mounted in spaced relationship with respect to the exterior of the car and extending along the 35 edge of said opening which is a leading edge when the car is moving in one direction, said vane being canted with respect to said outer surface with its plane extending substantially toward the center line of said air inlet.

40 6. In railway car construction, an outer wall structure the outer surface of which extends substantially in the direction of car movement, means forming an air inlet with an inlet opening through said wall structure, said opening having two edges substantially at right angles to the direction of car movement, and means to deflect air into said air inlet comprising a pair of flat vanes mounted on the exterior of the car with one vane extending along and being spaced outwardly from each of said two edges of said opening, each of said vanes having two edges extending at right angles to the direction of car movement with one edge of each vane positioned further from said opening than the other edge.

45 7. In combination with a railway car in which air is delivered through an air inlet on the outer surface of the car which inlet has its inlet opening in an outer surface extending in the direction of car movement, means to deflect air toward 50 said opening comprising, a pair of vanes posi-

tioned along opposite edges of said inlet opening which edges are the leading and trailing edges when the car is moving, each of said vanes being mounted along one dimension substantially parallel with the adjacent portion of said outer surface and along the other dimension at an acute angle with said adjacent portion—whereby movement of the car in one direction causes one vane to act as a leading vane, and movement of the car in the other direction causes the other vane 10 to be the leading vane, and whereby the air flow adjacent said opening is caused to flow evenly and air pressure conditions are created in the immediate vicinity of said opening.

15 8. In combination with a railway car in which air is delivered through an air inlet on the outer surface of the car which inlet has its inlet opening in an outer surface extending in the direction of car movement, means to deflect air toward said opening comprising, a pair of vanes positioned 20 along opposite edges of said inlet opening which edges are the leading and trailing edges when the car is moving, each of said vanes along one dimension being in parallel relationship with respect to said outer surface but being canted such 25 that along the other dimension it is at an acute angle with respect to said outer surface.

30 9. In railway car construction, an outer wall structure the outer surface of which extends in the direction of car movement, means forming an air inlet with an inlet opening through said wall structure, a louver construction mounted in said inlet opening and adapted to hinder the passage of moisture and foreign particles to said inlet, and means to deflect air into said air inlet comprising a vane mounted on the exterior of 35 the car and spaced outwardly from said opening, said vane extending substantially parallel to the outer surface of said wall structure and at right angles to the direction of movement of the car 40 with a space between said vane and said wall structure through which air flows to said opening.

45 10. In railway car construction, an outer wall structure the outer surface of which extends in the direction of car movement, means forming an air inlet with an inlet opening through said wall structure, a frame construction hingedly mounted in said inlet opening, a louver structure mounted in said frame construction, and means 50 mounted on said frame construction to deflect air through said louver structure to said inlet comprising a vane mounted on the exterior of the car and spaced outwardly from said opening, said vane extending substantially parallel to the outer surface of said wall structure and at right 55 angles to the direction of movement of the car with a space between said vane and said wall structure through which air flows to said opening.

JOHN D. STROBELL. 60
